UNITED STATES PATENT OFFICE.

CYRIAC DU BRUL, OF NEW YORK, N. Y.

CIGAR-MOLD.

SPECIFICATION forming part of Letters Patent No. 239,035, dated March 22, 1881.

Application filed January 25, 1881. (No model.)

To all whom it may concern:

Be it known that I, CYRIAC DU BRUL, a citizen of the United States, residing at New York, in the county of New York and State of New York, have invented Improvements in Cigar-Molds, of which the following is a specification.

The object of my invention is to enable the two parts of a cigar-mold to be readily separated by pressing apart at one end without the danger of breaking or injuring the thin edges of the cups most remote from the end to which the separating-pressure is applied. For this purpose I provide at one end of the mold, on the bed or cap, or both, a rise or projection to constitute a fulcrum-bearing when separating-pressure is applied at the other end of the mold, and adjustable in height, so as to gage the closure of the mold, as herein-after described.

In order that the invention may be fully understood, I will proceed to describe it with reference to the accompanying drawings, in which—

Figure 1 is a perspective view of the ends of the bed or body of a cigar-mold illustrating my invention. Fig. 2 is a longitudinal vertical section of both parts of the mold. Fig. 3 is an end view.

A represents the bed or body of the mold, and B the cap or follower thereof, formed with any desirable number of matrices or cups, C C, of required form.

D D are studs or dowel-pins, by which the parts of the mold are held and guided in proper relation to each other.

At the end 1 of the bed A of the mold is preferably formed an incline, E, forming a cavity for the reception of the fingers of the operator, or any suitable instrument by which

the mold is pried apart. At the other end, 2, of the mold I provide a rise or projection, F, which, in the present illustration, is shown on the bed A, but may be formed on the cap B; or, if preferred, projections may be formed both on base and cap, the effect being in either case to bring the projecting part or parts of the bed or body of the mold and the cap or follower nearly in contact at this point 2, so that when the mold is to be separated pressure applied at the opposite end, 1, will lift the matrices apart by a direct movement, and the lips or edges of the cups will thus be protected from danger of breakage, which with molds of ordinary construction is quite liable to occur to the first two cups.

It is found desirable to make the rise or projection F variable in height, so as to gage the closure of the mold and agree with the thickness of the cup-flanges, which differ much with different cups and different molds. For this purpose the said rise or projection is formed of a sliding piece, as shown, having an inclined bottom resting on a correspondingly-inclined base or bearing, and fixed in any position to which it may be adjusted by set-screws G, which may be arranged to bear either against its face or ends, as preferred.

Having thus described my invention, the following is what I claim as new and desire to secure by Letters Patent:

A cigar-mold constructed, substantially as herein described, with a rise or projection, F, of variable height, adjustable to correspond with the thickness of the mold-flanges or to gage the closure of the molds, as explained.

CYRIAC DU BRUL.
